DESIGN FOR A LABEL BLANK

Margaret Y. Flint, Westport, Conn., assignor to Peter Paul, Inc., Naugatuck, Conn., a corporation of Connecticut

Application January 4, 1936, Serial No. 60,417

Term of patent 3½ years

To all whom it may concern:

Be it known that I, Margaret Y. Flint, a citizen of the United States, residing at 41 Ludlow Road, in the county of Fairfield and State of Connecticut, have invented a new, original, and ornamental Design for a Label Blank, of which the following is a specification, reference being had to the accompanying drawing, in which one of the longer sides of the sheet is the top, forming part thereof.

The figure is a plan view of a label blank showing my new design.

I claim:

The ornamental design for a label blank, as shown and described.

MARGARET Y. FLINT.
